CLAIM

The ornamental design for a pencil holding clip, as shown and described.

DESCRIPTION

FIG. 1 is a front elevational view of a pencil holding clip showing my new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a second right side view thereof; and,

FIG. 8 is a third right side view thereof.

The magnet and suction cup indicated in broken lines in FIGS. 7 and 8 are intended to illustrate the manner in which the claimed design can be used and form no part of that design.

The characteristic feature of my design resides in the pair of particularly-configured clips attached to the front of the article, as best shown in FIGS. 1, 3 and 4.
